CHECK FOR PICKER-STICKS FOR LOOMS.

1,353,387.

Specification of Letters Patent. Patented Sept. 21, 1920.

Application filed August 29, 1919. Serial No. 320,599.

To all whom it may concern:

Be it known that I, SAYERS D. EUBANKS, a citizen of the United States, residing at Hillsboro, in the county of Orange and State 5 of North Carolina, have invented certain new and useful Improvements in Checks for Picker-Sticks for Looms, of which the following is a specification.

This invention has reference to checks for 10 picker sticks for looms, and its object is to provide a cheap and efficient structure whereby the picker stick may be gradually checked and rebound of either the picker stick or shuttle may be avoided.

15 In accordance with the invention, the check is provided with relatively soft and tough material which may be of fibrous nature and of which leather may be taken as an example, although other materials may 20 be used. However, leather is to be preferred as being peculiarly adapted for the purposes of the invention.

The invention comprises a bracket for attachment to the lay of the loom and on this 25 bracket there is mounted a rockable arm under the control of a suitable spring. The bracket is furnished with a stud about which the arm is capable of rocking and the arm is put under tension and urged against a 30 stop on the bracket by the spring. The bracket is also provided with a guide about which the leather strap connecting the two ends of the arm is directed, so that the strap may be always under tension and yet will 35 yield to a glancing blow given to the strap by the picker stick, thereby checking the latter easily yet quickly and without shock or jar so that no harm may occur to either the picker stick, the check or the shuttle.

40 The invention will be best understood from a consideration of the following detailed description taken in connection with the accompanying drawing forming part of this specification, with the understanding, 45 however, that the invention is not confined to any strict conformity with the showing of the drawing, but may be changed and modified so long as such changes and modifications mark no material departure from the 50 salient features of the invention as expressed in the appended claims.

In the drawings:

Figure 1 is a front elevation of a portion 55 of the right hand side of a loom showing the picker stick engaging the check.

Fig. 2 is a bottom plan view of the check

and a portion of the lay of the loom shown in Fig. 1, with the picker stick in cross section, the whole however being drawn on a larger scale than Fig. 1.

60

Fig. 3 is an elevation, on the scale of Fig. 2, showing the lay of the loom in vertical cross section.

Fig. 4 is a section on the line 4—4 of Fig. 2, but omitting both the lay and the picker 65 stick.

Referring to the drawings there is shown a picker stick A and a picker check B with which the picker stick is associated. The picker stick A is arranged to travel along 70 the lay C of the loom. The picker stick and the lay require no special description, while the check B is provided with a bracket 1 having an angle extension 2 at one end, and said bracket is appropriately slotted as indicated at 3 for attachment to the lay C. The extension 2 has an angle prolongation 4 constituting a table supporting an arm 5 which is provided with a laterally expanded flat 75 head 6 held to the table 4 by the set screw 7 80 through an interposed washer 8, the table 4 being provided with a boss 9 through which the screw 7 extends and which in turn extends through the arm 5 to produce a broad bearing. The arm 5 has a tail-like extension 85 10 expanded in a direction at right angles to the plane of the pivoted portion of the arm, and this tail-like extension has a thickened extremity 11 tapped to receive a screw 12. The thickened extremity is designed to 90 have one end of a strap 13 folded about it and held to it by the screw 12 so that pull of the strap is borne by the thickened extremity 11 and by the screw 12, wherefore 95 there is little or no tendency of tearing the strap from the screw.

The screw 7 enters a post 14, holding it on the table 4 and this post has the end remote from the table 4 reduced in size, as shown at 15, and has a square termination 100 with a perforation 16 for the passage of a cotter pin 17. The reduced end 15 of the post 14 receives a sleeve 18 with the exterior of about the same diameter as the body of the post 14. The sleeve 18 has an 105 offset return portion 19 in spaced relation to the post 14. Attached to the return portion 19 by a screw 20 is the other end of the strap 13. Surrounding the post 14 and sleeve 18 is a spring 21 which may be of helical form with one end 22 seated in a notch 110 or groove 23 in the corresponding end of the

post 14 to anchor such end of the spring. The other end of the spring has a prolongation 24^a for engaging the return portion 19. By rotating the post 14 while the screw 7 is loosened the spring 21 may be put under any desired degree of tension and then the screw 7 is tightened to hold the spring in such position. Under these circumstances a shoulder 24 on the extension or table 4 is engaged by a stop member 25 on the arm 5 maintaining the spring under the desired tension. If, now, force be applied to the strap 13 near the outer end of the tail 10 of the arm 5 the spring will yield to such force, provided it is strong enough. The strap 13 moving about a retaining and guiding flange 26 projecting from the table 4 at about right angles thereto and curved on an arc permitting the strap to conform thereto without any sharp bends and maintaining the portion of the strap between the flange 26 and the terminal portion 11 of the wing 10 substantially straight.

When the shuttle, indicated at dotted lines in Fig. 1, reaches the picker stick it is traveling at high speed and consequently the picker stick is forced toward the right as seen in Fig. 1, coming in contact with the strap 13 adjacent to the tail end or extremity 10 of the arm 5 and between said tail end 10 and the retaining and guiding flange 26. The impact of the picker stick A overcomes the resistance of the spring 21 causing the unsupported portion of the strap 13 and the tail like extremity 10 of the arm 5 to move with increasing resistance due to the winding of the spring and the friction between the strap 13 and the flange 26. While the checking of the picker stick and consequently of the shuttle, is rapid in the matter of time, its effect is gradual, wherefore all shocks and jars are avoided, the stick being thus eased into position by the check and rebound to the shuttle is prevented. The movement of the check under the impact of the shuttle and picker stick is indicated by the arrow E in Fig. 2.

In actual practice the travel of the stick under the impact of the shuttle against the opposition of the check is about two inches. The check follows the stick in the opposite direction as the shuttle is driven across the loom until stopped by the adjustment provided and is then ready to receive and check the shuttle on its return travel toward the first considered position.

When the picker stick strikes the check it engages the strap 13 close to the end 11 of the arm 5, thus engaging the yielding and relatively soft surface of the strap 13, causing the arm 5 to turn about the axis of the screw 7 and pulling the other end of the strap about the friction surface 26. This maintains the strap under considerable tension and the whole strap yields to the im-

pact of the picker stick, neither end of the strap being fixed. The lengthwise yielding of the strap is due to the yielding of the spring 21.

What is claimed is:—

1. A check for picker sticks for looms comprising a flexible strap, supports for both ends of the strap holding the intermediate portion of the strap tight with both ends of the strap movable in the same direction about a common axis, and elastic means common to both ends of the strap and arranged to yield to the impact of the shuttle against the picker stick and through the latter to the check. 70

2. A check for picker sticks for looms comprising a flexible strap, supports for both ends of the strap holding the intermediate portion of the strap tight with both ends of the strap movable in the same direction about a common axis, and elastic means common to both ends of the strap and arranged to yield to the impact of the shuttle against the picker stick and through the latter to the check, said check including 85 a friction plate engaged by the strap and elongated in the direction of the length of the strap. 90

3. A check for picker sticks of looms, comprising a rotatable member, an arm rotatable about the same axis as the rotatable member, a spring connected to the rotatable member for imparting thereto a rotative tendency in one direction, and a strap for location in the path of the picker stick to 100 be engaged thereby between its ends, said strap being fast at one end to the rotatable member and at the other end to the rotatable arm. 95

4. A check for picker sticks of looms comprising a support, an arm with a tail-like extension and pivotally mounted on the support to rock with respect thereto, a member also pivotally mounted on the support concentric with the axis of movement of the arm, a strap fast at one end to the tail-like extension and at the other end to the support and constituting a connection between the arm and support to cause them to move together, a spring connecting the arm and support and tending to maintain the strap in a taut condition, and a guide in the path of the strap and arranged in spaced relation to the tail-like extension of the arm to provide an unbacked part of 110 the strap constituting a yieldable impact surface for the picker stick. 115

5. A check for picker sticks of looms comprising a support, an arm with a tail-like extension and pivotally mounted on the support to rock with respect thereto, a member also pivotally mounted on the support concentric with the axis of movement of the arm, a strap fast at one end of the tail-like extension and at the other end to 125 130

- the support and constituting a connection between the arm and support to cause them to move together, a spring connecting the arm and support and tending to maintain 5 the strap in a taut condition, and a guide in the path of the strap and arranged in spaced relation to the tail-like extension of the arm to provide an unbacked part of the strap constituting a yieldable impact 10 surface for the picker stick, the guide being in the form of a fixed flange extended in the direction of travel of the strap to provide frictional resistance to the lengthwise movement thereof.
- 15 6. A check for picker sticks of looms, comprising a bracket with a table extension, an arm pivotally mounted at one end on the table and provided with a tail extending away from the table and located in substantially right angular relation thereto, a 20 flange on the table, a yieldable support on the table, and a strap fast at one end to the yieldable support and at the other end to the tail end of the arm, the latter being under the control of the yieldable support 25 through the strap, and said arm and table having coacting stop means for limiting movements of the arm about the spring support.
- 30 7. A check for picker sticks for looms comprising a support with a post thereon, a screw for holding the post in place, a sleeve on the post, a spring carried by the post and sleeve with one end of the spring fast to the post and the other end fast to the sleeve, an arm carried by the screw as a pivot and projecting away therefrom, and a strap fast at one end to the sleeve and at the other end to the arm with the tendency 35 of the spring such as to rotate the ends of the strap in the same direction, and the support and arm having engaging stop parts opposing the movement of the spring in one direction.
8. A check for picker sticks of looms 40 comprising a support with a post thereon, a screw for holding the post in place on the support, a rotatable sleeve on the post, a spring carried by the sleeve and post and connected at opposite ends to the respective 45 sleeve and post, an arm carried by and rotatable about the screw and provided with a tail-like extension, and a strap fast at one end to the sleeve and at the other end to the extremity of the arm of the tail-like 50 extension of the arm, the screw serving as a clamp member for the post to hold the latter and the spring in desired positions of adjustment to regulate the tension of the 55 spring.
- 60 In testimony whereof I affix my signature.

SAYERS D. EUBANKS.
